UNITED STATES PATENT OFFICE.

FERDINAND ALBERT POLKA, OF OAKES, DAKOTA TERRITORY.

GRAIN-DRILL.

SPECIFICATION forming part of Letters Patent No. 391,334, dated October 16, 1888.

Application filed April 24, 1888. Serial No. 271,664. (No model.)

To all whom it may concern:

Be it known that I, FERDINAND ALBERT POLKA, a citizen of the United States, residing at Oakes, in the county of Dickey and Territory 5 of Dakota, have invented a new and useful Improvement in Grain-Drills, of which the following is a specification.

My invention relates to an improvement in grain-drills; and it consists in the peculiar 10 construction and combination of devices that will be more fully set forth hereinafter, and particularly pointed out in the claims.

In the accompanying drawings, Figure 1 is a side elevation of a grain-drill embodying my 15 improvements. Fig. 2 is a vertical longitudinal sectional view of the same. Fig. 3 is a rear elevation, partly in section. Fig. 4 is a plan view. Fig. 5 is a detail view.

A represents a pair of longitudinal beams, 20 which are connected at their front and rear ends by cross-beams B C.

D represents a longitudinal beam, which is arranged midway between the beams A, connects the bars B C, and is adapted for the attachment of the tongue or pole. On the beams 25 A are knees or standards E, which support a transverse hopper, F, the latter being arranged in two compartments, G, and each of the said compartments having its sides and ends inclined downward, as shown.

H represents a shaft, which is journaled in bearings in the beams A and under the beam D, and on the said shaft are arranged a suitable number of circular disks or wheels, I, which 35 are equidistant apart and have their peripheries beveled on opposite sides, as shown, whereby the said wheels or disks are adapted to make furrows in the ground as the machine is drawn forward.

On the upper side of the beam C, and in line 40 with the centers of the hopper compartments G, are cylindrical cases K, each of which has one end closed and the opposite end open. Said cylindrical cases are connected to and 45 communicate with the lower sides of the hopper compartments by means of flexible tubes L, and in the centers of the closed ends of the said cases is journaled a transverse shaft, M. The said shaft is connected to the shaft H by 50 means of an endless belt, N.

One end of the shaft M is provided with radial wings O, which are arranged in one end of one of the cases K and are opposite the discharge opening P on the rear side of said case.

R represents a section, which is coupled to the 55 shaft M, extends longitudinally through the center of the other cylindrical case, and is provided at its inner end with radial wings T, which are similar to those previously described.

S represents a pair of cylindrical cut-offs, 60 which slide longitudinally on the shaft M and on the extension R thereof, and are arranged in the open ends of the cases K. The said cylindrical cut-offs have their ends which are nearest the closed ends of the cases counter-sunk and adapted to receive the wings T, so 65 that said cylindrical cut-offs may be moved entirely over the said wings, and thereby effectively cut off communication between the tubes L and the discharge openings of the cases, as 70 will be readily understood. Each cut-off S is provided near its outer end with an annular peripheral groove, T'.

U represents a lever, which is pivoted on the rear end of the beam D and projects rearward 75 beyond the beam C. A link, V, is connected to the said lever, and has arms or straps formed at its end, which engage the grooves T' of the cut-offs, and thereby the said cut-offs may be moved longitudinally in the cases K, so as to 80 open the discharge openings P or close the same to any desired extent by operating the lever U, as will be readily understood.

On the rear side of the beam C are secured the upper ends of a pair of seed-spouts, W, 85 each of which is arranged in rear of the discharge-opening of one of the seed-cases; and from the spouts W depend branches X, which first diverge downwardly, and are then bent downward in a vertical direction to form arms Y. On the said arms are secured vertically-adjustable tubular-hoes Z, which may be caused to operate in the ground at any desired depth.

A' represents a series of arms which have 95 their front ends hinged or pivoted to the beam C and extend rearward therefrom. The said arms are connected in pairs by U-shaped covers B', the lower ends of which are bent at suitable angles. On the same shaft or rod which serves as the pivot for the arms A' are pivoted 100

a number of bell-crank levers, C', which have their rearward-extending ends connected to the inverted ends of U-shaped coverers.

D' represents a rock-shaft, which is journaled 5 in bearings on the upper side of the beam E, and is provided with an operating-lever, E', and with a number of cranks, F', which latter are connected to the short vertical arms of the bell-crank levers by means of rods or links G'.

10 The operation of my invention will be readily understood. As the machine is drawn across a field the beveled edges of the wheels or disks open furrows. The seeds in the hoppers are fed through the tubes L into the cases K.

15 The shaft M is rotated by means of the endless belt which connects it to the shaft H, thereby causing the radial wings T on the shaft and its coupled section to rotate, and consequently force seeds from the cases K into the seed-20 spout, down which they fall into the furrows.

The coverers, which travel in rear of the machine, throw the dirt from opposite sides of the furrows into the same, and thereby effectually cover the seeds. By means of the bell-25 crank levers and the crank rock-shaft hereinbefore described the coverers may be raised from the ground when necessary, and by adjusting the cylindrical cut-off on the shaft in the cases K the quantity of seeds discharged

30 from said cases may be regulated at will.

Having thus described my invention, I claim—

1. The combination, in a grain drill, of the frame having the shaft H, provided with the supporting wheels or disks and arranged in 35 the center of the frame, the hopper, the standards E, supporting the same above the center of the frame, the force-feed seed-shaft, the cases in which the latter is journaled, arranged on the rear end of the frames, the 40 downwardly-inclined pipes or tubes L, connecting said cases to the hopper, the seed-spouts depending from the rear side of the frame, the pivoted arms A', extending rearward from the machine, and the U-shaped 45 coverers connecting the rear ends of said pivoted arms in pairs, substantially as described.

2. The combination, in a grain-drill, of the frame, the pivoted arms extending from the rear side of the frame, the coverers connected 50 to the said arm, the bell-crank levers attached to the coverers, the rock-shaft journaled on the front side of the frame and having the cranks and the operating-levers, and the rods or links connecting said cranks to the bell-crank levers, substantially as described. 55

In testimony that I claim the foregoing as my own I have hereto affixed my signature in presence of two witnesses.

FERDINAND ALBERT POLKA.
